SHOEMAKING

Walter James Smith and Alfred Richard O'Key, Leicester, England, assignors to United Shoe Machinery Corporation, Paterson, N. J., a corporation of New Jersey

Application July 6, 1932, Serial No. 621,066

In Great Britain July 18, 1931

3 Claims. (Cl. 12—1)

This invention relates to improvements in shoemaking and has particular reference to novel methods of tempering shoe bottom parts and novel means adapted to be employed in practicing such methods. Although not necessarily limited thereto, the present invention will herein be illustratively described with particular reference to tempering the channel flap of the outsole of a McKay-sewed shoe.

In the manufacture of McKay-sewed shoes, it is usually considered necessary that the outsole be in a tampered condition when certain operations, for example, channeling and leveling operations, are performed upon it and, therefore, it is a common practice to render the leather workable by moistening the sole. This is generally done before the sole is attached by placing the sole in water and then standing the sole on a bench or a special rack to permit surplus moisture to drain off and also to allow the moisture to penetrate well into the interior of the leather so as to render the sole mellow. If any substantial interval is to elapse before the sole is to be applied to a shoe, the sole may be retained in proper mellow condition by keeping it in a damp atmosphere until just before it is to be applied to the shoe, thus preventing excessive drying of the sole.

After the sole has been applied to the shoe, however, successive operations such as channeling, channel opening, sewing, and channel cementing operations are performed before the sole is ready to have its upstanding channel flap laid down and to be leveled and so, under normal factory conditions, a considerable interval will elapse between the time when the sole is applied to the shoe and the time when the channel laying and leveling operations are performed. In this interval and particularly under dry atmospheric conditions, the channel flap is likely to lose its moisture and become hard and unworkable. It will be appreciated that on account of the thinness of the channel flap the flap will tend to become dryer and harder than will the body portion of the sole. The channel laying operation is normally performed just before the leveling operation and in order to obtain the results referred to the channel flap should be moist and workable and since, as just indicated, the flap will often by this time have dried out to a hard and unworkable condition, it has sometimes been the practice to retemper the channel flap either by dipping the shoe bottom in water or by applying water to the sole with a sponge or a brush.

Such a procedure is disadvantageous, however,

for the following reasons. After leveling, the shoe has normally performed upon it those operations known in the trade as finishing operations and it is important that the shoe should be fairly dry before these finishing operations are performed. If, however, the channel flap and the adjacent sole margin have been moistened in the manner described just prior to leveling, the shoe will take some considerable time to become dry enough to permit the finishing operations to be performed and either an inconvenient delay in the progress of the work through the factory is caused at this stage or recourse must be had to more or less prolonged treatment in drying apparatus to dry the work. Furthermore, the wetting of the soles frequently produces stains which fail to disappear on drying and so make it necessary for the manufacturer to paint the bottom of the finished shoe instead of merely staining it or otherwise producing the so-called natural finish of the shoe bottom. The tendency to stain is more in evidence in cases where water is applied locally by means of a sponge or brush than in cases where the soles are tempered at an early stage of manufacture by uniform immersion. Thus, from the point of view of its liability to cause disfiguring stains upon the shoe bottom, the aforesaid methods of retempering the channel flaps are disadvantageous. Furthermore, prior to channel flap laying, the inside surface of the flap is usually coated with adhesive, for example, latex, which serves subsequently to hold the flap in laid down position. The effect of water applied to the flap either previous to or subsequent to the applying of the adhesive is usually detrimental to the holding power of the adhesive either through dilution or otherwise.

In view of the disadvantages inherent in the former practices above explained, an object of the present invention is to provide improved apparatus by which open channel-flaps on the bottoms of shoe-soles may be tempered, and by which hardened coatings of adhesive substance soluble by heat or moisture may be rendered tacky, both without staining the soles or depriving them of such adhesive substance.

In accordance with this object, the invention is herein exemplified as embodied in an apparatus comprising a casing forming a treatment chamber adapted to receive the entire tread-sole of a shoe, a substantially horizontal steam-constraining partition arranged in the chamber and having an opening larger than, but approximating the size and shape of a tread-sole, a work-supporting platform adjacent to, and in register

with the opening to permit emission of steam through the latter, and means for supplying steam in the casing below the partition.

The invention will be explained with reference to the accompanying drawing in which

Fig. 1 is a view in side elevation of apparatus for use in tempering the channel flaps on the tread soles of shoes;

Fig. 2 is a plan view of the apparatus;

Fig. 3 is a fragmentary side elevational view of a direct pressure-leveling machine such as may be employed in carrying out certain steps of the method;

Fig. 4 is an inverted plan view of a shoe illustrating the step of laying the channel flap of the tread sole; and

Fig. 5 is a side elevational view of the shoe illustrating the performance of a finishing operation upon the tread face.

In the practice of the improved method herein exemplified, the tempering of the channel flap on the tread sole of a shoe and the softening of latex thereon may both be accomplished by the use of apparatus such as that shown in Figs. 1 and 2 of the drawing. This apparatus comprises a casing forming a vertical chimney of which the upper portion 10 provides a treatment chamber, the lower portion 12 a steam-supplying chamber, and the intermediate portion 8 a connecting conduit. An opening 14 is provided at the front of the bottom portion of the apparatus to house heating means herein shown as a gas burner 16 supported upon a shelf 18 which is secured to the side walls of the apparatus by means of bolts and nuts 20. Immediately above the heating means a water container 22 is removably positioned. The container 22 comprises a shallow vessel which is supported upon flanges 24 and from the front of which projects a funnel 26. Water is supplied to the container 22 by drip feeding means comprising a reservoir 28 which, for purposes of obtaining comparatively large holding capacity, is made to embrace three sides of the chimney 8. The reservoir 28 is supported on a ledge 30 at the rear of the apparatus and is held securely in place on the chimney by means of a strap 32. The reservoir 28 may be filled with water through an opening in its upper wall on raising a hinged cover 34. Near the base of the reservoir an outlet tube 36 is provided and the rate of flow of liquid from the reservoir may be controlled by a valve 38. The lower end of the outlet tube 36 is located just above the funnel 26 of the container 22. Normally the valve 38 will be so adjusted that the container 22 will be supplied with water from the reservoir 28 at a rate just sufficient to compensate for the loss through evaporation as steam is formed.

The upper portion 10 of the tempering apparatus is of inverted truncated pyramidal form and contains a plurality of baffle-plates 40 by which the steam, constrained in the chimney 8 to flow upwardly therethrough, is evenly distributed throughout the cross-sectional area of the chamber in the portion 10. Above the baffle-plates 40 the steam is further constrained by a horizontal partition or plate 42 having two openings 44 (Fig. 2) through which the steam must escape before it can become dissipated in the atmosphere. These openings are of nearly the shape of a shoe-bottom but a little larger than the latter, their purpose being to expose for treatment the outsoles of shoes placed right side up in them or in register with them from above.

Shoes so placed are supported by platforms of reticulate construction which may be panels 46 of wire netting attached to the plate 42 around the openings 44 so as to fulfill their work-supporting duty without masking the shoe-bottoms or obstructing the flow of the steam to or along the tread faces of the outsoles. Preferably, the plate 42 and the panels 46 are curved to approximate the lengthwise curvatures of shoe bottoms. Secured to the rearward edge of the plate 42 is a member 48 the forward portion of which, as shown in Fig. 1, is located slightly above the level of the plate 42. This member 48 is provided with two notches or recesses each shaped to receive and register the toe portion of a shoe placed on the apparatus. The sides and rear portion of the top of the apparatus extend, at 50, above the level of a shoe placed in position on the apparatus, and guard the steam rising around both ends and both sides of a sole from the dissipating effect of external draughts.

According to one way of using the above-described apparatus, it may be placed by the side of a levelling machine of the direct pressure type, such, for example, as the machine disclosed in United States Letters Patent No. 1,275,562, granted August 13, 1918, upon application of Jerram and Gouldbourn and shown in Fig. 3 of the drawing of this application and in which shoes to be leveled are mounted upon oscillatory jacks that are moved alternately into position to be acted upon by leveling pads. Shoes will normally reach the leveling machine with the channel flap projecting and adhesively coated but in hard and unworkable condition, though the body of the sole, being, as already mentioned, thicker and slower to dry than is the channel flap, may still be mellow and in moderately good temper within, even though seemingly dry on its surface.

To prepare the channel flap for the laying operation and to improve the temper of the surface of the sole for the leveling operation, the operator takes a shoe, such as the shoe S, and places it over one of the apertures 44 in the plate 42. The gas burner 16 will have been adjusted so that the water in the container 22 is heated to such an extent that a steady but not too violent stream or current of steam at atmospheric pressure passes up the chimney 8 and impinges against the entire area of the tread of the sole including the channel flap. After the channel flap F (and also substantially the whole of the tread face T of the sole) has been subjected to the action of the impinging steam for a short period the operator will transfer the shoe to that one of the jacks 54 of the levelling machine which is at the time located in shoe-receiving position and will rub down the channel flap (which will be found to be in mellow and easily workable condition) with a sleeking tool, such as the tool 56 shown in Fig. 4, while the shoe is on the jack. After the channel flap F has been laid the jack is moved into position to be acted upon by a leveling pad (corresponding to the pad 58 shown in the drawing). Thereafter the shoe is removed from the leveling machine and, if desired, it may immediately be subjected to the customary bottom finishing operations one of which is illustrated in Fig. 5 70 wherein a finishing roll is indicated at 60.

It will be noticed that the construction of the steaming apparatus is such that the moistening effect of the steam is confined substantially to the shoe bottom none of the steam being di-

rected into the shoe and all of it being dissipated in the atmosphere as soon as it escapes from either of the openings 44. After the channel flap has been rubbed down the operator will 5 trip the levelling machine so that the jack 54 is carried forward and the shoe bottom is subjected to levelling pressure. While one shoe is being levelled the bottom of another shoe (resting on the same or on the other aperture 44) 10 may be steamed by the apparatus shown in Figs. 1 and 2 since the tempering proceeds without requiring attention or manipulation of the work on the part of the operator beyond the presentation of work to and its removal from the steaming apparatus. Thus no delay is caused through the operator's having to wait for a shoe to be steamed. In certain cases the operators of two 15 levelling machines may arrange to use a single steaming apparatus of the form just described. 20 In such cases the steaming apparatus would be located between the two operators and one operator would make use exclusively of the left-hand steaming aperture 44 while the other would use the right-hand aperture 44.

25 We have noticed that another advantage accrues from the use of the already described steaming method. McKay sewn shoes are commonly sewn with waxed thread. The effect of the steam is to soften the wax on the thread 30 and when the shoe is transferred to the levelling machine the wax will still be soft. When the channel flap is laid down and levelling pressure applied the flap will be forced down into contact with the plastic wax on the sewing thread or 35 protruding from the stitch holes which the flap covers. When the wax rehardens it apparently adheres to the channel flaps thus making the adhesion of the flap to the sole additionally secure.

40 It will be recognized that with the illustrative steaming apparatus already described substantially the whole of the shoe bottom is exposed to the action of the steam. Though the time of exposure is short the tempering effect of the 45 steam on the surface of the sole facilitates the levelling operation to a substantial extent.

Using the method hereinbefore described it is 50 found that the shoe bottom after levelling is not by any means in such a wet condition as it would have been had the previously employed method of applying water directly to the channel

flap immediately before channel laying been made use of and hence it is found that such small degree of dampness as is communicated by the steaming to the channel flap and the surface of the sole, whether on account of its being imparted under hot conditions or for some other reason, dries off very quickly, and as a result the shoe is in a suitably dry condition for finishing immediately after the levelling operation.

5

10

Having thus described our invention what we claim as new and desire to procure by Letters Patent of the United States is:

1. An apparatus for tempering the tread-soles of shoes, comprising a casing forming a treatment chamber adapted to receive the entire tread-sole of a shoe, a substantially horizontal steam-constraining partition arranged in said chamber and having an opening larger than, but approximating the size and the shape of, a 15 tread-sole, a work-supporting platform arranged adjacent to, and in register with, said opening to permit emission of steam through substantially the entire area thereof, and means for supplying steam in said casing below said partition. 25

2. A steaming device for use in retempering channel flaps on the soles of shoes comprising a receptacle for liquid, a reservoir from which the supply of liquid in said receptacle may be replenished, means for heating liquid in said receptacle, a chimney rising from said receptacle and having a flaring upper portion, a plate extending across the chimney above said flaring portion and below the top of the chimney, said plate having two openings therein, each of approximately the shape of a shoe bottom, and a sheet of wire netting beneath said plate constructed and arranged to support shoes placed bottom downward in said openings. 35

3. An apparatus for tempering the tread-face 40 of the sole of a shoe, comprising a substantially horizontal plate curved to approximate the lengthwise curvatures of the tread-face of the sole and having a sole-shaped opening slightly larger than the sole, a reticulate shoe-supporting 45 member extending across said opening, and means arranged to supply steam at atmospheric pressure to the bottom of a shoe standing on said reticulate member.
